UNITED STATES PATENT OFFICE.

LEWIS A. AMIS, OF MUSKOGEE, OKLAHOMA.

DESIGN FOR A LATHER-CUP.

56,577.

Specification for Design.

Patented Nov. 16, 1920.

Application filed June 28, 1920. Serial No. 392,524. Term of patent 14 years.

To all whom it may concern:

Be it known that I, LEWIS A. AMIS, a citizen of the United States, resident of Muskogee, county of Muskogee, and State of Oklahoma, have invented a new, original, and ornamental Design for a Lather-Cup, of which the following is a specification, reference being had to the accompanying drawings, forming part thereof.

Fig. II is a sectional view of the same, and

Fig. III is a bottom perspective view of the cup.

I claim:

The ornamental design for a lather cup, as shown.

LEWIS A. AMIS.
